(57) **CLAIM**

The ornamental design for a bottle, as shown and described.

DESCRIPTION

FIG. 1 is a side view of the bottle of the invention. The bottle is symmetrical, with all sides appearing the same;

FIG. 2 is a top view of the bottle of the invention; and,

FIG. 3 is a bottom view of the bottle of the invention. The broken lines shown in FIG. 3 of the drawing is understood to indicate that the pattern repeats uniformly around the circumference of the bottom surface.
